FIG-1

FIG-2

FIG-3

FIG-4

FIG-5

FIG-6

FIG. 1 is a perspective view of a microwave oven showing my new design.

FIG. 2 is a front elevational view thereof.

FIG. 3 is an elevational view of the right side thereof.

FIG. 4 is a top elevational view thereof.

FIG. 5 is a view thereof in perspective with the oven door open.

FIG. 6 is a side elevational view thereof with the oven door open.

The sides of the microwave oven are mirror images of each other. The back and bottom of the microwave oven are substantially plain and unornamented. The dotted surface pattern which is shown in FIG. 5 is understood to repeat throughout the indicated area.

We claim:

The ornamental design for a microwave oven, substantially as shown and described.
